UNITED STATES PATENT OFFICE.

JOHN RUFFING, SR., OF NOKOMIS, ILLINOIS, ASSIGNOR OF ONE-HALF TO WALTER D. GARDELS, OF NOKOMIS, ILLINOIS.

END DOOR FOR COAL CARS.

Application filed March 10, 1927. Serial No. 174,241.

This invention relates to new and useful improvements in coal cars and has more particular reference to an end door therefor, the invention aiming to provide means for disposition at the rear end of a coal car above the upper edge thereof for preventing the fall of the coal over the rear end of the car when the same is being coupled with other cars or being disposed upon a tipple which results in the loss of a considerable amount of coal, injury to the workmen, and the frequent tying up of the cars by reason of the derailment of the same which often times occurs when the coal drops from the cars onto the trackway.

A most important object of this invention resides in the provision of an end door of this character that is extremely simple in construction and that may be readily applied to coal cars now in use without in any manner whatever altering the construction thereof.

A still further and important object is to provide an end door of this character that may be readily swung over into the car if such is desired.

With the foregoing and other objects in view as the nature of the invention will be better understood, the same comprises the novel form, combination and arrangement of parts hereinafter more fully described, shown in the accompanying drawing and claimed.

In the drawing wherein like reference characters indicate corresponding parts throughout both of the views:

Figure 1 is a fragmentary rear end elevation of a conventional coal car, the rear end wall thereof being disclosed partially in cross section and said end wall being constructed with a door in accordance with the present invention, and

Figure 2 is a transverse section through the rear end of the car for disclosing my improved door in inner side elevation.

Now having particular reference to the drawing A designates fragmentarily a conventional mine coal car with which the

present end door is associated. In carrying out the present invention I bolt, rivet, or otherwise rigidly secure to the inner surface of the car rear end wall, a pair of vertically extending spaced angle bars 5—5, to the upper ends and inner faces of which are pivoted as at 6—6 a pair of similar angle bars 7—7, the lower ends of these bars 7—7 engaging within the interior of the car being clearly disclosed in both views. Bolted, riveted, or otherwise secured to the outer sides of the pivotal bars 7—7 at a point slightly above the upper edge of the rear end wall of the car A is a board 9, the ends 60 of which terminate within the side walls of the car as clearly disclosed in Figure 2.

In order that the bars 7—7 carrying the board 9 may be readily swung into the car, the lower ends of the board attached sides 65 of said bars terminate at the pivotal connections 6—6, while the lower ends of the pivoted sides of said bars 7—7 are rounded as indicated by the dotted lines in Figure 1.

Thus it will be seen that when the board 9 is swung upwardly into position over the rear end of the car A the coal within the car will be prevented from falling over the rear end thereof regardless of the shocks and jerks imparted to the same during the coupling of the car, and the beginning of movement of the same upon the track way.

Having thus described the invention, what I claim is:—

In a door for rear end walls of coal cars, a pair of angle bar members rigidly secured to the inner face of the said car wall terminating at certain ends at the upper edge of the wall, a pair of second angle bars extending at their lower ends into the car 85 pivotal connections between the adjacent flanges of the last mentioned bars and said first mentioned bars and a door board rigidly secured to the outer sides of said second mentioned bars so as to provide an extension 90 for the rear end of the car when the same is swung upwardly with respect thereto.

In testimony whereof I affix my signature.

JOHN RUFFING, Sr.
